Lacy & Lacy, Attorneys

UNITED STATES PATENT OFFICE.

FRANK FOX, OF CHESAW, WASHINGTON.

DRAG-SAW.

Application filed August 24, 1921. Serial No. 495,016.

To all whom it may concern:

Be it known that I, FRANK Fox, citizen of the United States, residing at Chesaw, in the county of Okanogan and State of Washington, have invented certain new and useful Improvements in Drag-Saws, of which the following is a specification.

This invention relates to an improved drag saw and has as one of its principal objects to provide a device of this character whereby a single person may quickly and easily fell trees.

The invention has as a further object to provide a device of this character wherein the body thereof may be adjustably elevated or lowered to meet varying requirements of practical working conditions.

And the invention has as a still further object to provide a device which will be characterized by structural simplicity and which, in use, will prove thoroughly efficient.

Other and incidental objects will appear hereinafter.

In the drawings:

Figure 1 is a perspective view showing my improved device in conjunction with a tree, the device being erected for felling the tree,

Figure 2 is a longitudinal section taken medially through the device,

Figure 3 is an inverted perspective view showing the head of the device in detail,

Figure 4 is a fragmentary section on the line 4—4 of Figure 2, looking in the direction of the arrows, and

Figure 5 is a detail plan view showing the guide roller employed for the free end of the saw blade, the tree supporting the roller being in section.

Referring now more particularly to the drawing, I employ a body bar 10 in which is a medial longitudinally directed slot 12 extending throughout the major portion of the length of the bar. Hinged to the outer end of the bar is one section 13 of a supporting leg, the other section 14 of which is adjustably connected to the first section by a bolt 15 extending through suitable slots in the sections. Thus, by loosening the wing nut of said bolt the effective length of the leg 14 may be readily varied. Extending between the leg at its inner side and the body bar is a folding brace 15'. Mounted upon the bar near its inner end is a horizontally disposed guide roller 16 upstanding from the bar and freely received in a suitable opening

therethrough and secured to the bar in advance of said roller is a head 17. As shown in detail in Figure 3 of the drawing, the head is preferably formed of a single length of suitable resilient sheet metal bent to provide overlapping top and bottom strips, the bottom strip extending beyond the top strip and the top strip being provided at its free end with an upstanding flange 18 overlying the outer end edge of the body bar. Extending through said strips and through the bar are bolts or other approved fastening devices 19 securing the head upon the bar. Pivotally mounted upon the projecting end of the bottom strip of the head is an anchoring plate 20 notched to provide prongs 21 and carried by the plate is a bolt 22 freely received through an arcuate slot 23 in said strip. Thus, as will be seen, the plate 20 may be adjustably swung upon the head and secured in adjusted position by the bolt 22.

Mounted upon the body bar is a cross head comprising top and bottom plates 24 confronting opposite sides of the bar and extending between said plates through the slot 12 of the body bar are pins 25 and 26 connecting the plates, the cross head being, of course, slidably longitudinally of the bar. Mounted upon said pins within the slot 12 are rollers 27 adapted to coact with the side walls of the slot for supporting the cross head to freely move longitudinally of the bar and connected at one end to the upper end of the pin 25 is a spring 28, the opposite end of which is secured to a pin 29 driven into the bar, the spring normally holding the cross head retracted. Secured at one end to the pin 26 of the cross head is an appropriate saw 30 and mounted upon the free end of the saw is a suitable handle 31.

In Figure 1 of the drawing, I have shown my improved device in conjunction with a tree, set up for felling the tree. As will be observed, the prongs 21 of the anchoring plate 20 upon the head 17 of the device are sunk into the tree at the level of the cut to be made, the body bar being arranged to extend radially from the tree and being supported at its outer end by the leg 14. Since the section 14 of this leg may be readily adjusted, as previously noted, the body bar may be easily disposed in horizontal position, while the spaced prongs 21 will prevent side swaying of the body bar. The handle 31 of the saw may therefore be

grasped and the saw reciprocated for cutting through the tree, the spring 28 operating to retract the saw each time it is drawn forwardly. The roller 16 is provided for sustaining the free end portion of the saw so that the saw will be held out of contact with the head 17 while provision is made for adjustment of the anchoring plate 20 so that the forward end of the body bar 10 may be shifted laterally in either one direction or the other, as the cutting operation progresses, without the necessity for disconnecting the anchoring plate from the tree. Driven into the tree just below the 15 level of the cut to be made is a pin 32 upon which is mounted a roller 33 for guiding the saw when starting the cut. It will accordingly be seen that I provide a particularly simple and effective construction for 20 the purpose set forth and while I have shown the preferred embodiment of the invention still, as will be appreciated, various minor changes or modifications, as may be dictated by practical use, may be made therein. I accordingly reserve the right to all 25

such variations as may fall within the spirit of the appended claims.

Having thus described the invention, what is claimed as new is:

1. In a drag saw, the combination of a 30 body bar, a head mounted upon one end thereof and provided with an arcuate slot, an anchoring plate pivotally connected to the head for adjustment laterally with respect to the bar, means carried by the plate 35 to extend through said slot securing the plate in adjusted position, and a saw blade carried by the bar for movement longitudinally thereof.

2. In a drag saw, a body bar, a plate 40 bent to form a head projecting at one end of the bar and having a stop flange engaging the adjacent end edge of the bar limiting the plate against rearward movement upon the bar, means connecting said plate 45 to the bar, an anchoring plate adjustable upon said head, and a saw blade carried by the bar for movement longitudinally thereof.

In testimony whereof I affix my signature.

FRANK FOX. [L. S.]
